CLAIM

I claim the ornamental design for a beverage container insert, substantially as shown and described.

DESCRIPTION

FIG. 1 is an upper perspective view of beverage container insert showing my new design;

FIG. 2 is a lower perspective view thereof;

FIG. 3 is a side view thereof taken along a corner, the opposing side view being the same;

FIG. 4 is a side view taken along a side surface, the opposing side view being the same;

FIG. 5 is a top view thereof;

FIG. 6 is a bottom view thereof;

FIG. 7 is a perspective view of the beverage container insert in an exploded environmental use; and,

FIG. 8 is a perspective view of the beverage container insert in an assembled environmental use.

The broken lines shown in the drawings depict portions of a beverage container that form no part of the claimed design.
